UNITED STATES PATENT OFFICE

115,009

DESIGN FOR A GLASS DISH

Maurice A. Smith, Jeannette, Pa., assignor to
McKee Glass Company, Jeannette, Pa., a cor-
poration of Pennsylvania

Application July 7, 1938, Serial No. 78,324

Term of patent 7 years

To all whom it may concern:

Be it known that I, Maurice A. Smith, a citizen of the United States, residing at Jeannette, in the county of Westmoreland and State of Pennsylvania, have invented a new, original, and ornamental Design for a Glass Dish, of which the following is a specification, reference being had to the accompanying drawing, forming part thereof, in which Figure 1 is a bottom plan view of a glass dish showing my new design, and Figure 2 a front elevational view thereof partially in section.

The characteristic feature of my design consists in a bowl-shaped glass dish having a plain-surface inner wall and having its outer wall formed of a series of graduated semi-spherical protuberances over substantially the entire base and sidewall of the dish, said protuberances being of gradually diminishing size from the base to the mouth of the dish all as shown.

I claim:

The ornamental design for a glass dish, as shown and described.

MAURICE A. SMITH.
